Application May 13, 1932, Serial No. 611,014

7 Claims. (Cl. 96—3)

This invention relates to strands and a method of assembling them, and more particularly to the continuous braiding of textile coverings for conductor cords.

5 An object of the invention is to provide a strand assembly of a new and improved construction, and an improved method of producing the strand assembly.

In the preferred embodiment of the invention apparatus for moving a strand at different speeds and in forward and reverse directions through a braiding machine is provided in order that a braided covering may be applied to the strand which is of different texture or mesh, and which 10 is oppositely directed at different portions of the covering. The reversal of the direction of movement of the strand permits the braiding of a second layer of covering over the first, and the restoration of forward movement permits the 15 braiding of a third layer of covering, whereby a reinforcement comprising a plurality of layers of covering may be produced on portions of the strand. The braiding material connecting one of the layers to another may be severed to permit 20 the outer covering to taper uniformly over the end of a reinforcing portion.

These and other objects and advantages of the invention will become apparent from the following detailed description of one embodiment thereof, reference being had to the accompanying drawings wherein

Fig. 1 is a front elevational view of a braiding machine;

Fig. 2 is an elevational view of the side of the same machine on which the timing mechanism is carried;

Figs. 3 and 4, when placed side by side with Fig. 3 at the left of Fig. 4, show schematically in perspective the driving and controlling mechanism of the braiding machine;

Figs. 5 and 6 show in elevation an electrical cord in partial stages of completion;

Fig. 7 shows in elevation a completed cord in accordance with the invention, and

Fig. 8 is a top plan view of the driving and controlling mechanism of the braiding machine.

Referring to the drawings, in which like reference numerals designate corresponding parts throughout the several views, and particularly to Figs. 1 and 2, the strand assembling machine which embodies the invention has a frame 10 mounted on legs 11. Secured to diagonally opposite corners of the frame 10 are upright posts 12 and 13 which support a cross member 14.

The frame 10 supports a braiding head 18 of any

well known type consisting of the usual rotatable carriers for carrying the inner and outer sets of bobbins or cops 19 and 20, respectively, of any suitable braiding material, preferably in the form of strands, such, for example, as thread or twine, the carriers being rotated by the motor 22, which is supported by the frame 10, through the motor shaft 23, gears 24 and 25, shaft 28, bevel gear 29, and toothed ring 30 (shown in Fig. 8). The braiding head 18 is mounted in the stationary housing 32 supported by brackets 33 on the frame 10.

As shown in Figs. 1, 2 and 3 a cylindrical tube 34 having a supporting flange 35 is vertically supported in the frame 10 in coaxial relation to the 15 rotatable bobbin carriers. The tube 34 has slidably mounted therein a cylindrical tube 36 which extends above the top of the tube 34. The tube 36 is provided with a plurality of holes 37 arranged in vertical alignment and adapted to 20 receive a removable pin 39 carried by the tube 34 for selectively positioning and securing the tube 36 with respect to the tube 34.

Mounted at the top of the tube 36 is a collar 25 45 which is internally grooved to receive a plurality of cutter members 46 having oblique cutting edges at opposite ends thereof. The cutter members may be secured in the collar 45 in any suitable manner, and are provided with 30 two cutting edges in order that they may be turned end for end when the upper end becomes dull. A hollow mandrel tube 47 extends through the collar 45 coaxially thereof, and the mandrel 35 47 is provided with longitudinal grooves 48 over a considerable portion of its length to receive the inner edges of the cutter members 46. The cutter members thus center the mandrel in the collar 45, the grooves of the mandrel cooperate with those of the collar to retain the cutters, and by reason of the fact that grooves of the 40 mandrel are longer than the cutters, relative axial movement between the mandrel and the collar 45 is permitted. The mandrel tube is provided at its upper end with a conical tip 49 having a shoulder 44 where it joins the main body of the 45 mandrel, the tip 49 being slotted to correspond to the grooves of the mandrel. In the normal or lowered position of the mandrel the cutting edges of the cutter members are disposed within the slots in the tip 49 at a point slightly above the 50 shoulder 44.

The mandrel 47 fits into and is supported at its lower end by a block 50 which has oppositely extending pins 51 passing through elongated slots 52 in the lower portion of the tube 36 and en-

gaging the endless chains 53 by means of which the block 50 is supported. The chains 53 are supported by and operated upon the upper and lower sprockets 55 and 56 respectively, the 5 sprockets 55 being supported on the shaft 57 to drive the chains, the sprockets 56 being supported on the shaft 58 which is journaled in the members 59 supported by the legs 11. The shaft 58 has journaled thereon intermediate the sprockets 10 56 a sheave 62 for guiding a strand. The chains 53 support a shaft 63 which has journaled thereon a sheave 64 also for guiding a strand. At the base of the machine, brackets 67 are provided for supporting a supply reel 68 containing a continuous supply of strand 69 which is to receive a braided covering. At the top of the machine, on the member 14, is mounted a bracket 70 which supports a freely rotatable multi-grooved sheave 71. The upright post 13 supports 15 a bracket 72 in which is journaled a shaft 73 which has its axis substantially parallel to the axis of the sheave 71. A multi-grooved capstan 75 is keyed to the shaft 73 in alignment with the sheave 71. The capstan 75 is employed to 20 advance a strand through the machine, and it is driven by the shaft 73 in a manner which will presently be described. At the base of the machine, brackets 78 are provided for supporting a take-up spool 79 which is mounted on a shaft 80 and is driven in a manner to be described later.

The path of a strand or group of strands that is to receive a braided covering is upward from the supply spool 68, over sheave 64, downward 35 and under the sheave 62, up through the interior of the hollow mandrel 47, and out at the top of the braiding head. The material from the bobbins 19 and 20 is applied to the strand to form the braided covering just above the braiding head, 40 as indicated at 84, which is the braiding point. A guard bracket 85 having an aperture through 45 which the braided cord may pass is mounted on the member 14 and has the guard portion 86 to prevent the braiding point from exceeding the desired distance above the braiding head. A vertically bored member 88 is secured to the member 14, and from the braiding point the braided cord passes through the guard portion 86 of the member 85 and through the member 88 to the first groove of the sheave 71 and then to the first groove of the capstan 75. The sheave and the capstan are preferably each provided with four grooves, so that the cord may advance four times to the capstan and return 50 three times to the sheave. From the last groove of the capstan the cord goes to take-up spool, 55 and is reeled thereon.

The drive for the capstan 75, the take-up spool 79, the chains 53 and for timing mechanism 60 which will presently be described is obtained from the shaft 28 which drives the rotatable bobbin carriers, and which is driven by the motor 22. The shaft 28 has keyed thereto a bevel gear 90 that meshes with a bevel gear 91 carried by a shaft 92, which extends into a gear box 93. The gear box contains change speed and reverse gearing shown in Fig. 4.

Referring to Fig. 4, the shaft 92, which is journaled in the gear box 93, has freely rotatable 70 thereon the gears 100, 101, and 102, each of which has secured thereto a notched or toothed hub or collar, represented by the reference numerals 104, 105, and 106 respectively. The gears 100, 101, and 102 differ from each other in size and number of teeth, in the preferred arrangement, the gear 100

being the largest, the gear 101 spacedly adjacent thereto being the smallest, and the gear 102 being of a size intermediate those of the other two. The shaft 92 has mounted thereon intermediate the gears 100 and 101, a collar 108 which has teeth at its opposite ends corresponding to the teeth of the hub members 104 and 105. The collar 108 is loosely splined or keyed to the shaft 92 so as to be rotatable therewith and slidably thereon, and it has an annular groove 109 in the periphery thereof in which is disposed a yoke portion 110 of a lever 111 which is pivotally mounted at 112. By rocking the lever 111, the collar 108 may be moved into engagement with either of the hub members 104 and 105 to establish driving connection between 15 the shaft 92 and either of the gears 100 and 101.

The shaft 92 also carries adjacent to the hub member 106 of the gear 102 a collar 115 having teeth at one end thereof for engagement with the toothed hub member 106. The collar 115 is loosely 20 splined or keyed to the shaft 92 to rotate therewith and slide thereon, and is provided with an annular groove 116 in which is disposed a yoke 117 of a lever 118 that is pivoted at 119. Thus the collar may be moved into engagement with the hub 25 member 106 to establish driving connection between the shaft 92 and the gear 102.

The gear box 93 has journaled therein a shaft 125 which has its axis substantially parallel with the axis of the shaft 92. The shaft 125 has keyed 30 thereto three gears 126, 127 and 128, meshing respectively with the gears 100 and 101, and with the idler 129 which meshes with the gear 102. It follows from the previously stated relationships between the sizes of the gears 100, 101, and 102, 35 that of the gears on the shaft 125, the gear 127 will be largest and have the greatest number of teeth, the gear 126 will be smallest and have the smallest number of teeth. The gear 128, in the preferred embodiment of the invention, is of a size intermediate the gears 126 and 127. The shaft 125 has secured thereto, a gear 130 from which the drive for all operating parts of the machine except the bobbin carriers is obtained. When the collar 108 is in engagement with the hub member 104, the 45 shaft 125 is driven at its maximum velocity. When the collar is in engagement with the hub member 105, the shaft 125 is driven in the same direction, and at its minimum velocity. When the collar 108 is in its central position, and the collar 50 115 is in engagement with the hub member 106, the shaft 125 is driven at an intermediate velocity, and by reason of the idler gear 129, in a reverse direction.

The gear 130 has meshing therewith a gear 131 55 carried by a shaft 132, which also carries a sprocket 134. The sprocket 134 engages an endless chain 133 which operates upon the sprockets 134 and 135, and the idler sprockets 136. The sprocket 135 is carried by a shaft 138 which also 60 carries the sprockets 139 and 140, and the gear 141, all of which are keyed to the shaft 138. The sprocket 135 is the driving connection between the chain 133 and the shaft 138, so that the shaft 138 is driven from the shaft 132, and in the same 65 direction as the latter shaft.

The sprocket 139 which is secured to the shaft 138 engages and drives an endless chain 145 which also engages and drives a sprocket 146 secured to a shaft 147 from which the take-up reel 79 is 70 driven. The shaft 147 carries a pulley 148 which is preferably loosely mounted thereon and rotatably connected thereto through a clutch mechanism of any suitable construction, and preferably operable to drive only in one direction. In the 75

drawings, the clutch mechanism comprises a toothed member 150 secured to the pulley 148 and a cooperating toothed member 151 slidably keyed to the shaft 147 and urged into engagement with the member 150 by a spring 152. The teeth of the members comprise cooperating shoulders and inclined surfaces, whereby the pulley is positively driven when the shaft 147 is rotated in one direction, and is disengaged when the shaft is rotated in the opposite direction. The pulley 148 is connected by a belt 154 to a pulley 155 secured to a shaft 156.

The shaft 156 is supported by and journaled in a lever arm 158 which is journaled at its opposite end on the take-up spool shaft 80. The lever arm 158 supports a weight 157, by means of which the belt 154 is kept under sufficient tension to drive the shaft 156. The shaft 156 has secured thereto a gear 160 which meshes with a gear 161 secured to the take-up shaft 80. It is thus apparent that a driving connection is established between the shaft 138 and the take-up spool to effect rotation of spool upon rotation of the shaft 138 in a predetermined direction. The teeth of the clutch mechanism are so arranged that the take-up spool will be driven to wind an advancing strand, but will not be driven to unwind. The tensioning arrangement including the lever arm and weight permits slippage between the belt 154 and associated pulleys, and thereby allows the speed of rotation of the take-up spool to vary as the quantity of strand applied thereto increases. A strand distributing mechanism of any well known type, represented generally by the reference character 162 in Fig. 1, is also driven by the chain 145.

The sprocket 140 which is secured to the shaft 138 operates an endless chain 165 to drive a sprocket 166 which is secured to a shaft 161. The shaft 161 has secured thereto a gear 169 which meshes with a gear 170 that is secured to the capstan shaft 73. The capstan 75 is thus connected by the gearing, sprocket, and chain to the shaft 138, and is positively driven thereby in either direction as determined by the direction of rotation of the shaft 138.

As previously stated, the shaft 138 has secured thereto a gear 141. This gear meshes with an idler gear 173 which in turn meshes with a gear 174 secured to a shaft 175. The shaft 175 has secured thereto a sprocket 177 which supports and drives an endless timing chain 178 that is also supported by an idler sprocket 179. The apparatus associated with and controlled by the timing chain will presently be described.

As previously stated, a shaft 57 has secured thereto the sprockets 55 for operating the chains 53 to elevate the hollow mandrel tube 47. The shaft 57 extends through and is journaled in a stationary supporting member 185 which is provided with teeth or notches at the end farthest from the sprockets 55. A second stationary support 186 for the shaft 57 has journaled therein a sleeve 184 which has secured thereto at the end nearest to the sprockets 55 a collar 187 provided with teeth or notches similar to those of the member 185. At its other end, the sleeve 184 has secured a sprocket 189 which meshes with and is driven by the endless chain 133. The shaft 57 is also journaled in the sleeve 184 and has slidably splined or keyed thereto, intermediate the toothed members 185 and 187, a collar 190 which is provided at both ends with teeth corresponding to those of the adjacent members. The collar 190 is provided with an annular groove 191 in the periphery thereof which receives one end of a lever

arm 192 that is pivoted at 193. It follows from the above description that by rocking the lever arm 192 in the proper direction, the collar 190 may be moved into engagement with the rotating collar 187 to rotate the sprockets 55 and move the chains 53 to elevate the mandrel tube 47, or it may be moved into engagement with the stationary member 185 to positively lock the chains 53 and mandrel tube in a stationary position.

It has previously been stated that the strand 10 guiding sheave 64 is carried by a shaft 63 that is supported by the chains 53. Fig. 3 clearly indicates this construction, as well as the fact that when the mandrel tube is elevated, the sheave 64 will descend an equal distance, and the path of the 15 strand from the supply reel to the lower guiding sheave will be shortened. The tension on the strand at the supply reel will thus be reduced, the strand that advances to the braiding point with the mandrel will include the surplus from 20 the strand path, and less than enough to accompany the mandrel will be unreeled. When the mandrel descends, the strand path will increase in length, and some of the strand which would accumulate as slack will be absorbed into the strand 25 path. Thus the amount of slack caused by the descent of the mandrel will be less than it would be with an unvarying strand path.

Referring to Figs. 2, 3 and 8 a timing bar 200 having an elongated slot 201 therein is pivotally supported parallel to and above the timing chain 178 by lever arms 202 and 203 pivotally mounted in stationary supports 204 and 205 respectively. The pivot shaft 206 which carries the lever arm 203 has secured to the other end thereof a lever arm 35 209 which is disposed in the path of one of the pins 51 that support the mandrel block 50. The lever arm 203 supports a counterweight 210 which cooperates upon movement of the timing bar 200 in either direction to insure full movement of the 40 bar and associated levers. The timing bar 200 has mounted on the upper surface thereof a bracket 212, and at one end an arm 213 extending out in alignment with the bar and having at its outer end a portion 214 extending transversely of the bar. 45 The bar also carries a lug or stop 214 adjustable longitudinally of the bar and secured in any predetermined position by any suitable means such as a screw 215 extending through the slot 201. When the timing bar is in the position shown in 50 Fig. 3, the lug 214 is disposed in the path of a pin 216 carried by the timing chain 178, the normal movement of which is in the direction indicated by the arrow. When the pin advances into engagement with the lug it imparts a longitudinal movement to the timing bar, which is suspended from the lever arms 202 and 203, and which therefore suffers an accompanying upward movement, until the lug 214 clears the pin.

Mounted on the frame of the machine adjacent 55 to the timing bar bracket 212 is a rock shaft 220 which supports mercury switches, preferably two in number, identified by the reference numerals 221 and 222. Each of these switches consists of a tube of suitable material, such for example, as 60 glass, closed at both ends, and partially filled with mercury. Each tube has two or more contact electrodes sealed therein and extending into the tube to have an electrical circuit therebetween closed by the mercury when the tube is tipped to 65 flow the mercury into contact with the electrodes. The switch 221 preferably has two electrodes whereby one circuit is closed or opened upon 70 rocking the shaft 220. The switch 222 preferably has three electrodes, so that one circuit is opened 75

and one is closed upon rocking the shaft 220 in either direction. The shaft 220 has mounted thereon at the end adjacent to the bracket a lever arm 223 which is connected by the tension spring 224 to the bracket 212. The spring 224 is so positioned that a short longitudinal movement of the timing bar will cause the spring to move across the axis of the rock shaft 220 and exert a tension on the upper end of the lever arm 223 to rock the shaft. The bracket 212 has a hook shaped portion at the upper end which, when the timing bar moves to rock the switches 221 and 222 from the dotted position to the full line position, will bear against the lever arm 223 until the spring passes the axis of the shaft 220 and exerts a tension on the lever arm to complete the movement thereof. The lever arm will then be drawn out of the path of the hook shaped portion of the bracket, and it will not interfere with the movement of the timing bar.

Near the end of the timing bar that carries the arm 213 is journaled in a stationary support a rock shaft 230 which supports a mercury switch 231 that is preferably provided with two contact electrodes. The shaft 230 is connected by a lever arm 232, a connecting link 233, and a lever arm 234 to a rock shaft 236 which has secured thereto a lever arm 237 disposed in the path of the timing chain pin 216 and in the path of movement of the portion 211 of the arm 213.

The cylindrical tube 36 carries near its lower end a support for a rock shaft 240 which has secured thereto a mercury switch 241, preferably having three contact electrodes, and a lever arm 242. The tube 36 also carries a lever 244 pivoted thereto at 245 and urged in an upward direction by means of the tension spring 246. The lever 244 is disposed below and in the path of one of the mandrel supporting pins 51, and its outer end is connected by a tension spring 247 to the outer end of the lever arm 242. When the mandrel supporting block 50 is in its lowermost position, the pin 51 keeps the lever 244 depressed to maintain the mercury switch 241 in the position shown in full lines. When the block rises due to movement of the chains 53, the lever 244 pivots about the point 245 under the influence of the spring 246 to carry the spring 247 past the axis of the rock shaft 240 to rock the shaft and move the switch to the position shown in broken lines.

The several positive clutches which have previously been described for effecting speed changes in the driving mechanism and for controlling the operation of the chains 53 are operated by electromagnetic means, preferably solenoids. Current for energizing the solenoids may be obtained from any convenient source of electrical energy, such as the usual one hundred ten volt line consisting of the conductors 248 and 249, the latter of which 60 may have one side of a double pole switch 250 therein for completing the circuit. The other side of the switch 250 is connected in one side of a power line 251 of suitable potential for operating the motor 22. A solenoid 252 has its armature 253 pivotally connected to the lever 192 which controls the clutch collar 190, the arrangement being such that when the solenoid is energized, the collar is kept in engagement with the stationary member 185, and when the solenoid is deenergized, a tension spring 254 connected to the lever 192 draws the collar into engagement with the rotatable member 187. One side of the winding of the solenoid 252 is connected by a conductor 255 to an end contact of the mercury switch 241, the center contact of which is connected by a conductor 258

to the conductor 249 of the power line. The other side of the solenoid winding is connected by a conductor 257 to one of the contacts of the mercury switch 231, which has its other contact connected by a conductor 259 to the conductor 248 5

The lever 118 which operates the reversing clutch collar 115 is normally held to keep the collar 115 out of engagement with the hub member 106 by a tension spring 262, and is pivotally connected to the armature 263 of a solenoid 264. The solenoid is energizable to draw the collar into engagement with the toothed hub member 106. One side of the winding of the solenoid 264 is connected by a conductor 266 to the third terminal of the mercury switch 241, and the other side of the winding is connected by a conductor 267 to an end terminal of the mercury switch 222, the center terminal of which connects through the conductor 259 to the line conductor 248. 20

The lever 111 which operates the high and low speed forward clutch collar 108 has the transversely extending arms 270 and 271 to which are pivotally connected the armatures 272 and 273 respectively of the solenoids 274 and 275 respectively. The solenoids 274 and 275 are respectively energizable to move the collar 108 into engagement with the hub member 104 or 105. The tension spring 276 maintains the collar in a central or neutral position when both of the solenoids 30 are deenergized. The solenoid 274 has one side of its winding connected by a conductor 278 to the third contact of the mercury switch 222, and the other side of its winding is connected through the conductor 258 to the line conductor 249. The 35 solenoid 275 has one side of its winding connected by a conductor 279 to one of the terminals of the mercury switch 221, the other terminal of which connects through the conductor 259 to the line conductor 248. The other side of the winding of the solenoid 275 is connected to the conductor 256 which connects to a terminal of the mercury switch 241, as previously described.

Mounted adjacent to the lever 111 is a rock shaft 281 which has secured thereto a mercury switch 282, preferably having two contacts, and a lever arm 283. A member 285 is secured to and extends from the arm 271 of the lever 111, and a tension spring 286 connects the member 285 to the lever arm 283. The parts are so arranged that when the clutch collar 108 is in engagement with the hub member 105 by reason of energization of the solenoid 275, the mercury switch will be so positioned as to complete the circuit between its contacts. However, when the clutch collar is in either of the remaining positions, the spring 286 will have passed across the axis of the shaft 281 to rock the shaft and open the circuit through the switch.

As shown in Fig. 1, the bracket 70 which is supported by the cross member 14 has pivotally mounted thereon an arm 288 which supports at its outer end a single grooved sheave 289. The arm and sheave are in alignment with the strand 65 as it first advances from the sheave 71 to the capstan 75, so that the sheave 289 may ride above and in contact with the strand. The cross member 14 has mounted thereon a solenoid 290, the armature 291 of which is pivotally connected by a 70 link 292 to the arm 288. The arrangement is such that when the solenoid is energized, the sheave 289 is drawn down, to place the strand under tension. One side of the solenoid winding is connected through the conductor 259 to the line con- 75

ductor 248, and the other side of the winding is connected by a conductor 293 to one terminal of the mercury switch 282, the other terminal of which connects through the conductor 258 to the line conductor 249.

As shown in Figs. 2 and 8, the actual mechanism for operating the forward driving and reversing clutches differs slightly from the arrangement shown schematically in Fig. 4. The armatures of the solenoids 274 and 275, the latter of which cannot be seen in Fig. 2, are pivotally connected to a lever 295 which is pivotally supported at 296. A rock shaft 297 which is operatively connected to the yoke 110 of Fig. 4 extends through the wall of the gear box 93 and carries exteriorly thereof a lever 298 which is connected by a tie rod 299 to the lever 295. It is thus apparent that the rocking movement of the lever 295 in response to the operation of either of the solenoids will result in an angular movement of the lever 298 and a rocking of the shaft 297.

The yoke 117 of Fig. 4 which operates the reversing clutch 115 is operatively connected to a rock shaft 300 which extends from the gear box 93 and carries externally thereof a lever 301 comprising the angularly extending arms 302 and 303. A lever 304 which is pivotally supported on the shaft 297 is connected at one end by a tie rod 309 to the armature of the solenoid 264. The other end of the lever 304 is bifurcated to receive the end of the arm 302 which has an elongated slot (not shown). A pin 305 extends through the bifurcated end of the lever 304 and through the slot in the arm 302 of the lever 301 to operatively connect the two levers. Thus, when the solenoid 264 is energized, the tie rod 309 is drawn downwardly, the lever 304 is rocked in a clockwise direction, and the lever 301 and rock shaft 300 are rocked in a counterclockwise direction to engage the reversing clutch.

The arm 303 carried by the lever 300 cooperates with a lever 306 secured to the rock shaft 297 to form an interlock between the two clutch operating mechanisms to prevent concurrent engagement of the forward driving and reversing clutches. The lever 306 is provided at its outer end with a V-shaped notch 307, and the arm 303 carries a pin 308 which is disposed within the notch. When the reversing solenoid operates, the lever 301 rocks to move the pin 308 to the center of the notch, and the forward driving clutch must be in its neutral position in order for the pin to move to the center of the notch. The notched lever is then prevented from moving, and the forward driving clutch cannot be engaged. When either the high speed or low speed clutching arrangement is in operation, if the reversing solenoid should be energized, the pin 308 will be obstructed by one or the other of the walls of the notch near the outer end thereof, and will be prevented from moving to the center of the notch, which it must do in order for the reversing clutch to be engaged. In this way the clutches are interlocked so that the operation of both at the same time is precluded.

It has previously been stated that one of the purposes for which a machine embodying the invention may be employed is the continuous braiding of switchboard cords having reenforced portions comprising a plurality of layers of braided covering. In one instance the strand to which a braided covering is to be applied consists of a plurality of insulated conductors, preferably three, which have been twisted, together with filler twines, to form a substantially cylindrical

strand, and around which a retaining serving of twine has been wound to maintain the twisted strands in the desired arrangement. A portion of such a strand is shown in Fig. 5 in which there are the insulated conductors 310, the filler twines 311, and the retaining serving 312. When such a strand is to receive a braided covering, a reel containing preferably an unbroken length of the strand may be mounted in the hereinbefore described supply reel support, and the strand may be threaded into the machine in the manner also previously described.

It should be remembered that the bobbin carriers rotate at a continuous velocity, while the linear velocity of the strand is changed at predetermined intervals by the change speed gearing. The number of turns of braiding material received by the strand per unit of length is therefore a function of the velocity of the strand. When the strand is travelling at its minimum velocity, the greatest number of turns of braiding material per unit of length is applied, and the braid is described as a slow or close-meshed braid. Conversely, when the strand is travelling at its maximum velocity, the least number of turns of braiding material per unit of length is applied, and the braid is described as a fast or open-meshed braid. The closeness or tightness of the braid varies inversely as the velocity of the cord. This may readily be observed by including on one of the bobbin carriers a bobbin of tracer material of contrasting character, allowing the machine to operate through a cycle of speed changes, and noting the distance between adjacent turns of the helix of tracer material at each speed.

In the preferred form of the cord, the major portion of each cord length is covered with a single covering of braid of relatively close mesh, as shown at 315 in Fig. 7, and this mesh is defined as the normal or slow braid. After the normal braid has been applied for a predetermined distance, a speed change occurs in the machine which results in an increase in the velocity of the strand, and the application of a fast or open braid thereto, as shown at 316 in Figs. 5, 6 and 7. After the open braid has been applied for a predetermined distance which is preferably relatively short as compared with the normally braided portion and has been applied over the tip 49 of the mandrel 47, the direction of advance of the strand is reversed, and its velocity is changed to a value to produce a mesh intermediate those of the normal and fast braid. The reversal of the strand results in the braiding of a second layer 317 superimposed upon the fast braid; this layer in the preferred embodiment being somewhat shorter than the fast braid, as shown in Figs. 5 and 6. When the second layer has been applied to a predetermined length of strand, the cutter members previously described operate to sever and cut away portions of the twine at the point where they doubled back upon reversal of the strand as shown at 318 in Fig. 6. Substantially simultaneously with the operation of the cutters, the strand is again reversed to advance it in the normal direction, and the strand velocity is changed to that which produces the normal braid. A third layer of braiding is thus superimposed on the other two layers, as shown at 319 in Figs. 6 and 7, and this braiding tapers smoothly over the severed twines at the end of the extra layers, and continues as a normal single layer 315 applied to newly presented portions of the strand. The cycle may be repeated until the end of the strand contained on the supply reel is reached, after

which the braided strand may be severed a plurality of times in equal lengths, to produce a plurality of cords, each of which has a reinforced portion at a predetermined position on the card.

- 5 Preferably, the strand is severed in the open-meshed braid near the point of the beginning of the outer or normal braid, which is the end of the reenforced portion opposite to the tapered portion. Thus a cord has the reinforcement at 10 one end and a length of exposed open-meshed or fast braid at each end. A connection terminal such as a switchboard plug may be secured to the reenforced end, thus providing the reenforced portion at the place where the cord is 15 subject to much handling. At the other end, the open-meshed braid may easily be removed or pushed back to expose the conductor strands for connection purposes.

Describing in detail the operation of a braiding machine constructed in accordance with the invention to produce conductor cords as previously described, Figs. 3 and 4 show the switch 250 closed, to supply electrical energy to the motor 22 and to the several mercury switch and solenoid circuits to render the machine operative. The strand is properly strung through the machine from supply reel to take-up reel and a normal braid is being applied thereto by reason of the fact that the solenoid 275 is energized 25 to maintain the slow speed clutch comprising the members 105 and 108 in operative engagement. The mandrel tube 47 is at its lowest position and the solenoid 252 is energized to maintain the clutch member 191 in engagement with the stationary member 185, thus locking the shaft 51. The reversing clutch comprising the members 106 and 115 is disengaged and the timing pin 216 is approaching the lug 214 carried by the timing bar 200. As the timing chain advances 30 in the direction indicated by the arrow, the timing pin is brought into engagement with the lug 214 and as it advances the timing bar is also advanced in the same direction to rock the shaft 220 and change the mercury switches 221 and 222 from the full line position to the dotted position. The movement of the timing bar also rocks the shaft 208 to move the lever 209 from the full line position to the dotted position.

- The movement of the switch 221 opens the circuit from the line conductor 248 through the conductor 259, through the conductor 279, through the solenoid 275, through the mercury switch 241 and through the conductor 258 to the line conductor 249 whereby the solenoid 275 is deenergized to disengage the slow speed clutch. The movement of the mercury switch 222 opens a circuit through the conductor 259, through the conductor 267, through the solenoid 264, through the conductor 266 to the mercury switch 241 which is also positioned to maintain this circuit opened, the return to the line conductor 249 being through the conductor 258. The circuit of the reversing clutch solenoid which was open at the switch 241 is also open at the switch 222. The switch 222 also closes the circuit from the line conductor 248 through the conductor 259, through the conductor 278, through the solenoid 274, through the conductor 258 to the line conductor 249 whereby the solenoid 274 is energized to draw the collar 108 into engagement with the hub member 104, thus completing the high speed drive. The movement of the arm 111 which operates a clutch member 108 causes the shaft 281 to rock, thus changing the mercury switch 282 from the full line position to the dotted position

and interrupting circuit from the line conductor 248 through the conductor 259, through the winding of the solenoid 290 and through the conductor 258 to the line conductor 249 whereby the solenoid 290 is deenergized to permit the advancing strand to draw the sheave 289 from the full line position to the dotted position.

The change from low to high speed in the gear box increases the velocity of the strand by increasing the velocity of the capstan 75 and the take-up 79. The speed changes thus described cause the fast or open-meshed braid to be applied to the strand. The timing chain continues to advance until the pin 216 engages and trips the lever arm 237 which causes the shaft 230 to be rocked to change the mercury switch 231 from the full line position to the dotted position. A circuit from the line conductor 248 through the conductor 259, through the switch 231, through the conductor 257 and the winding of the solenoid 252, through the conductor 256, through the mercury switch 241 and through the conductor 258 to the line conductor 249 is thus interrupted to deenergize the relay 252 and permit the spring 254 to move the clutch collar 190 into engagement with the rotatable member 187 which is driven by the sprocket 189. The mandrel elevating chains 153 are thus operatively connected to the chain 133 to cause the mandrel to move upwardly toward the braiding point at approximately the same velocity as the velocity of the strand.

The movement of the mandrel tube upwardly permits the lever 244 to rotate about its pivot point and rock the shaft 240 to change the mercury switch 241 from the full line position to the dotted position. The change in position of the switch 241 causes the mandrel elevating solenoid circuit which was previously opened by the switch 231 to also be opened at the switch 241. The circuit of the slow speed operating solenoid 275 which was previously opened at the switch 221 is also opened at 241. The break in the circuit through the reverse operating solenoid 264 is now closed by the switch 241 so that it is open only at the switch 222.

The mandrel tube 47 continues to rise until it reaches the braiding point where the open-mesh braiding will be applied over the conical tip of the mandrel and under the shoulder at the base of the tip. When the mandrel tube has reached its uppermost position, one of the pins 51 will have engaged, the lever 209 and will have returned it to the full line position, thus rocking the shaft 208 to reset the timing bar 200 and the mercury switches 221 and 222 to their original positions. The switch 231 will also be returned to its original position by reason of the engagement of the portion 211 of the timing bar extension 213 with the lever arm 237. The switch 231 will close at that point, the circuit of the mandrel elevating solenoid 252 which, however, is still open at the switch 241. The resetting of the switch 221 will close the circuit of the slow speed solenoid 275 which also is open at 241. The resetting of the switch 222 opens the previously described circuit through the high speed solenoid 274 to permit the clutch member 108 to move to its intermediate or neutral position. At the same time the switch 22 closes the only remaining break in the circuit of the reversing solenoid 264 so that the solenoid is energized to draw the clutch member 115 into engagement with the hub 106 to reverse the direction of operation of the shaft 125, the shaft 132, the chain 133, the shaft 75

57, the shaft 138, the capstan 75 and the timing chain 173. The mandrel tube 47 thus begins to descend and it carries with it the strand by reason of the fact that braiding has been applied over the conical tip and under the shoulder. As 5 the strand moves downwardly, a second layer of braiding is applied over the first layer of fast and open-meshed braiding and the mesh of the second layer is intermediate the mesh of the normal and fast braid by reason of an intermediate gear ratio in the reversing gears.

In the take-up spool driving mechanism the chain sprocket ratios are such that the take-up reel tends to be driven at a strand reeling velocity 15 that exceeds the strand advancing velocity of the capstan 75, and the slippage permitted by the belt 154 enables the take-up reel to rotate at slower speeds to reel the strand as it is supplied. If the take-up reel were positively driven in the 20 reverse direction upon reversal of the movement of the strand, excessive amounts of strand would be unreeled, and upon restoration of the normal strand direction, the strand might slip on the capstan and remain stationary while the take-up reel was rereeling the excess. By employing the one way ratchet clutch, the driving portion thereof rotates in the reverse direction faster than the driven portion, which may rotate only fast enough to unreel the desired amount of 25 strand, which is drawn from the reel by the capstan, thus keeping the strand between the capstan and reel taut. Thus the take-up reel is ready, immediately upon restoration of the normal movement of the strand, to reel strand advanced by the capstan.

The mandrel continues to descend until one 35 of the pins 51 engages the lever 244 and moves it downwardly to rock the mercury switch 241 to its original position. The return of the switch to its original position causes the circuit through the 40 reversing solenoid to open and the circuits through the mandrel solenoid 252 and the slow speed solenoid 275 to be closed so that those 45 solenoids are energized to lock the mandrel in the lower position and to operate the mechanism at the minimum speed to return to the normal or slow braiding.

When the mandrel 47 has been drawn to its lowest position, the cutter members 46 enter 50 the slots of the conical tip and the twines which form the braiding are severed by the cutter members at the point where the first reversal occurred. By reason of the inter-twined arrangement of the braiding twines, some of them will 55 be severed in one place and others will be severed in two or more places so that small pieces of the twine will be removed from the braiding. These pieces are permitted to fall through the hollow tube 36 to the bottom thereof from which they may be removed in any suitable manner such as 60 by suction means not shown.

The sheave 229, which is drawn against the strand by the solenoid 290 at the beginning of the slow speed advance of the strand, prevents pil- 65 ling of the braid at or near the point of beginning of the normal braid by causing a sudden shift of the strand in the direction of advance.

With the return of the switch 241 to its original 70 position all of the mechanisms driven from the shaft 92 return to their normal operation and the outer or normal braid is applied over the two layers previously applied. The third layer continues to be applied until the lower end of the reenforced position where the twines were 75 severed approaches the braiding point. The se-

rance of the twines permits the ends thereof, which may be of varying lengths, to be arranged evenly and flatly against the body of the strand so that the normal braiding continues over the severed threads to newly presented portions of the strand in a smooth and even taper. If the cord should be braided without severing the threads at the junction of the first and second reenforcing layers, an abrupt change in the diameter of the strand might, in some instances, 10 result at that point, so that after the outer braid was applied, a covered shoulder would exist in the strand, and when used in the conventional type of switchboard, excessive wear on the cord might result at the shoulder. The normal braid- 15 ing of a single cover for the strand continues until the timing pin 216 is advanced to engage- 20 ment with the lug 214 when the above described cycle of operations is repeated.

As shown in Fig. 3, the timing pin 216 extends 25 from the inner and outer sides of the timing chain, and its inner portion engages the lug 214 to actuate the mechanism to produce exposed open-meshed braid and its outer end engages the lever arm 237 to actuate the mechanism to pro- 30 duce reenforcing layers. It is apparent that ad- 35 ditional pins similar to the pin 216 may be mounted on the chain in equal or unequal spac- 35 ing arrangement to produce a plurality of cor- 40 respondingly spaced reenforcements preceded by 40 exposed open-meshed braid, during one cycle of 45 operation of the timing chain.

It is also possible to change the nature of the 45 strand assembly by providing one or more pins 50 extending only from the outer side of the chain 55 to engage only the lever arm 237. Such pins 55 would cause the production of reenforced por- 60 tions having open-meshed braid as a foundation 65 for the reenforcement, but having no exposed 70 open-meshed braid. For example, one pin ex- 75 tending from the outer side of the chain might 80 be provided in advance of the pin 216, to produce 85 a reenforcement immediately following the nor- 90 mally braided body portion of the cord, and hav- 95 ing no exposed open-meshed braid. This pin may 100 be so spaced from the pin 216 that immediately 105 upon the completion of this reenforcement, the 110 pin 216 may operate to produce a short length 115 of exposed open braid, followed by a reenforce- 120 ment. In this way, a strand may be braided 125 which has alternate closely spaced and relatively 130 widely separated reenforced portions, the closely 135 spaced reenforcements being separated by ex- 140 posed open-meshed braid, and the portion be- 145 tween the widely separated reenforcements hav- 150 ing normal braiding thereon. The strand may 155 be severed in the portions having the exposed 160 open braid, thus producing cords having reen- 165 forced portions near each end, and open-meshed 170 portions at the ends to facilitate the exposure 175 of the conductors for connection purposes. 180 Other arrangements of pins may be employed 185 to produce reenforcements with or without ex- 190 posed open braid at desired intervals on the 195 strand.

The apparatus hereinbefore described is ad- 200 justable at several points to vary the dimensions 205 of component parts of the braided cover for a 210 cord, and also the length of a complete cord. If 215 the sprocket 134 is removed and another is sub- 220 stituted therefor which is larger or smaller, and 225 which has more or less teeth, the chain 133 will 230 be driven correspondingly faster or slower to 235 render the mesh of the braiding at all speeds 240 closer or more open in the same proportion. The 245

lengths of the cord, the reenforced portion, and the several types of braiding will remain unchanged, but since the quantity of twine applied to unit length of the strand is a function of the strand velocity, the mesh of all of the types of braiding will be altered in proportion to the increase or decrease in the velocity of the chain 133.

The length of strand that receives reenforcing layers of braiding is determined by the distance between the top of the mandrel and the braiding point, which is the path of travel of the mandrel. This distance may be altered by varying the height of the cylindrical tube 36 with respect to the tube 34, the holes 37 and pin 39 being provided for that purpose. The effect of reducing the distance of travel of the mandrel is to reduce the length of the reenforced portion by an equal amount. Since the open braid is applied from the time the timing bar is tripped until it is reset at the termination of the upward movement of the mandrel, the length of the open braid will be reduced by the same amount, the reduction occurring in the portion covered by the reenforcing layers. The portion of the open braid that is exposed, the length of the normal braid, and the overall length of the cord remain unchanged. An increase in the distance from the mandrel to the braiding point produces in the cord similar changes in opposite sense.

The lug 214 carried by the timing bar is made adjustable by means of the slot in the bar in order that its distance from the lever arm 237 may be varied. This distance determines the quantity of open braiding that is exposed, and therefore the quantity of normal braiding that is applied. If the distance is increased, the length of the portion of the cord having exposed open braiding is increased, and the length of the portion having normal braiding is decreased by the same amount. Conversely, a decrease in the distance decreases the open braid and increases the normal braid by equal amounts. Changing the position of the lug 214 does not affect the length of the reenforced portion, nor the overall length of the cord.

It is also possible to vary the overall length of the cord. This may be accomplished by changing the size of either of the gears 141 and 174 to change the gear ratio therebetween. For facilitating such a change, the idler gear 173 may be mounted on a movable support 176, so that it may mesh with a larger or smaller gear 141 or 174. The effect of this is to change the operating period of the timing chain without affecting the speed of the capstan 75 that advances the strand. An increase in the speed of operation of the timing chain will decrease the time required to complete a cycle, and since the capstan speed is not affected, a smaller amount of strand will reach the braiding point, and the cord will be shorter. The shortening, however, will occur in the normal braiding and in the exposed portion of the open braiding, but the length of the reenforced portion will not be affected, as it is determined entirely by the distance of travel of the mandrel. A reduction in the operating speed will increase the length of the cord by increasing the normal braid and the exposed portion of the open braid, and as before, the length of the reenforced portion will remain constant.

It is to be understood that the making or changing of one of the above described adjustments 75 does not preclude the changing of any of the

others, but that all of the adjustments are compatible and may be made or changed at any time to vary the length of the cord, the length of the reenforced portion, the relative lengths of normal and exposed open braid, and the texture of mesh of the braids, to satisfy any desired conditions.

The operation of cutters 46 and the mandrel 47 may be briefly summarized as follows: As the braid 316 (Fig. 5) is nearing completion the mandrel 47 (Figs. 1, 2, 3 and 5) is raised so that the braid 316 is applied over the mandrel head 49 (Figs. 1, 2, 3 and 5) at which time the motion of the mandrel 47 is reversed so that the second braid 317 is applied over the mandrel head 49 as shown in Fig. 5 and continued up over the first braid 316 as the braided portion is pulled downward into the machine by means of the gripping action of the braids 316 and 317 on the mandrel head 49. The tube 36 (Figs. 1, 2 and 3) carrying cutters 46 (Figs. 1, 2 and 3) is positioned so that when the desired length of the second braid 317 is completed the mandrel 47 will have brought the cutting edges of the blades 46 into the slots 48 (Fig. 5) to the junction of the straight portion of the mandrel 47 and the conical tip 49, thereby bringing the junction of the braids 316 and 317 down past the upper cutting edges of the cutters 46 and causing them to slit the two braids for a short distance longitudinally. At this time the motion of the mandrel 47 is arrested and the cord again moved in a forward direction by means of the capstan, starting the application of the third braid 319 (Fig. 6) and pulling the two braids 316 and 317 off of the mandrel head 49, thereby causing the threads forming the braids 316 and 317 to fray out as shown at 318 (Fig. 6). The motion of the cord is continued in a forward direction so that the third braid 319 is continued downward over the cut ends of braids 316 and 317, which results in a gradual change in the diameter of the cord as shown in Fig. 7.

Although in the drawings and foregoing description, one embodiment of a conductor cord and of a method and apparatus and arrangement of parts for braiding it have been shown and described, it should be understood that the invention is not limited to the particular embodiment shown and described, but that it contemplates and is capable of many changes, substitutions, and modifications within the scope of the appended claims.

What is claimed is:

1. A method of assembling strands, which comprises braiding a plurality of threads upon a moving strand to form a covering therefor, reversing the threads and braiding a second covering over a portion of the previously braided strand, severing the threads at the point of reversal, reversing the threads and braiding a covering over the second covering, over the severed threads, and over newly presented portions of the strand.

2. A method of assembling strands, which comprises loosely braiding a plurality of threads upon a strand for a portion of its length, reversing the threads and more tightly braiding the threads in a reverse direction over a portion of the loose braiding, severing the braiding and cutting away portions thereof at the point of reversal, reversing the threads substantially simultaneously with the cutting, and still more tightly braiding an outer covering over the reverse braiding, and over the main body of the strand, and again applying a loosely braided portion spaced from the other.

3. In a strand assembly, a core, a braided cover-

ing of predetermined mesh extending over a portion of the length thereof, a second braided covering of different mesh extending over a portion of the first covering, and a third braided covering differing in mesh from the other two, and extending over the second braided covering and over the principal portion of the core.

4. In a strand assembly, a core, a braided covering extending over a portion of the core, a second braided covering doubled back over the first and severed from the first, and a third braided covering doubled back over and continuous with the second covering and tapered over the severed ends of the first and second coverings.

5. In a strand assembly, a core, and a braided covering therefor including a loosely braided portion at one end, a reenforcing portion at the other end comprising a plurality of layers of braided material, and a tightly braided portion extending from the loosely braided portion to the

reenforced end and tapered over one end of the reenforcing layers.

6. A method of assembling strands which comprises the steps of continuously braiding a continuous covering normally of one layer upon a moving strand and forming the same covering at predetermined intervals and over predetermined distances to produce three continuously interconnected superimposed layers, and severing the braiding material connecting the inmost layer to the intermediate layer.

7. A method of assembling strands which comprises the steps of continuously braiding a continuous covering normally of one layer upon a moving strand and forming the same covering at predetermined intervals and over predetermined distances to produce three continuously interconnected superimposed layers.
